UNITED STATES PATENT OFFICE

OSWALD G. SEIDENSTICKER, OF CHICAGO, ILLINOIS, ASSIGNOR TO THE PAYSON MANUFACTURING COMPANY, A CORPORATION OF ILLINOIS

DESIGN FOR A PUSH AND PULL BAR

Application filed December 4, 1929. Serial No. 33,638. Term of patent 7 years.

To all whom it may concern:

Be it known that I, OSWALD G. SEIDENSTICKER, a citizen of the United States, residing at Chicago, in the county of Cook and State of Illinois, have invented a new, original, and ornamental Design for Push and Pull Bar, of which the following is a specification, reference being had to the accompanying drawings, forming a part thereof.

Fig. 1 is a face view of a push and pull bar showing my new design;

Fig. 2 is a side elevation; and

Fig. 3 is an end elevation of the same.

I claim:

The ornamental design for a push and pull bar as shown.

In testimony whereof I have hereunto affixed my signature.

OSWALD G. SEIDENSTICKER.
